UNITED STATES PATENT OFFICE.

EPILIER E. SAVAGE, OF ASBURY PARK, NEW JERSEY.

SIGNAL DEVICE FOR VEHICLES.

1,068,278.

Specification of Letters Patent.

Patented July 22, 1913.

Application filed November 1, 1912. Serial No. 729,182.

To all whom it may concern:

Be it known that I, EPILIER E. SAVAGE, a citizen of the United States, residing at Asbury Park, in the county of Monmouth and State of New Jersey, have invented certain new and useful Improvements in Signal Devices for Vehicles, of which the following is a specification, reference being had to the accompanying drawings.

10 This invention relates to improvements in signaling devices for vehicles and has for its primary object to provide a device of this character for use upon automobiles and other motor driven vehicles whereby motorists 15 may be notified of the driver's intentions with regard to the direction in which the machine is to be turned.

Another object of the invention is to provide a device of this character which may 20 be readily converted from a day into a night signal or vice versa.

Another and more specific object of the invention resides in the provision of a lamp box, a rotatable pinte and door fixed thereto, 25 a second door loosely mounted upon the pinte, means for connecting said latter door to the first door of the lamp case, and means to be actuated by the driver to rotate said pinte and swing one or both of said doors 30 to its open position.

A still further object of the invention is to produce a signaling device of the above character which consists of comparatively few elements of simple form, durable in construction and efficient in operation and which 35 may be manufactured and installed upon various types of motor vehicles at comparatively small cost.

With the above and other objects in view 40 as will become apparent as the description proceeds, the invention consists in certain constructions, combinations and arrangements of the parts that I shall hereinafter fully describe and claim.

45 For a full understanding of the invention, reference is to be had to the following description and accompanying drawings, in which—

Figure 1 is a side elevation of the chassis 50 of a motor driven vehicle provided with my improved signaling device; Fig. 2 is a top plan view; Fig. 3 is a rear elevation; Fig. 4 is a perspective view showing the position of the foot lever when the doors of the lamp casing have been moved to their open posi-

tion; and Fig. 5 is a horizontal section through the lamp.

Referring in detail to the drawings, C indicates the chassis or frame of a motor driven vehicle and F the floor thereof. Upon 60 the rear end of the vehicle body and at each side thereof, a lamp L is mounted in any preferred manner, said lamps being preferably arranged approximately upon the level of the wheel guards. 65

Each of the lamps consists of a sheet metal casing 5 which is provided in its inner side walls with an uncolored plate of glass or other transparent material indicated at 6. The light rays are projected 70 through these glass plates upon the license plate indicated at P which is suitably arranged upon the vehicle between the lamps. The rear side of each lamp casing is provided with a door 7 which normally closes 75 the lamp casing. This door is fixed to the upper end of a rotatable rod or pinte 8, said pinte being suitably mounted in bearings provided upon the lamp case. A second door 9 is loosely mounted at one of its 80 edges upon the rod or pinte 8. The lower edge of this latter door terminates a slight distance above the lower edge of the outer door 7. To the inner face of the door 7 one end of a coil spring 10 is fastened; the other 85 end of said spring being fixed to the adjacent side wall of the lamp case 5. This spring normally acts to hold the door 7 in its closed position and prevent rotation of the pinte 8. The free edge of the inner 90 door 9 is provided with an eye 11 to receive a hook 12 on the lamp casing or a hook 13 attached to the free edge of the outer door 7. It will be apparent that when the latter hook is engaged in the eye 11, both of the 95 doors 7 and 9 will be swung as a unit to their open position when the pinte 8 is rotated. When, however, the eye 11 is engaged by the hook 12 on the lamp casing, only the outer door 7 will be swung open 100 upon the rotation of said pinte or rod.

The pinte rod 8 is extended downwardly below the lamp and has its lower end seated in a step bearing provided upon the bottom of a rectangular casing 14. Upon the lower 105 end of said rod and within the casing 14, a peripherally grooved wheel or pulley 15 is fixed. One end of a chain, cable or other flexible connection indicated at 16 is attached to the wheel 15 and is wrapped 110

around the same several times. The other end of this chain extends through an opening in one wall of the casing 14 and is connected to the end of a rod 17. It is of course to be understood that the structure described in the foregoing is duplicated at each side of the machine.

The rods 17 are extended forwardly above the frame of the vehicle and the driving gearing which is mounted therein, and in convergent relation to each other. The forward end of each rod is connected to the depending arm of a bell crank lever 18. This lever is fulcrumed in a hanger bracket 19 and the horizontal arm thereof is pivotally connected to the lower end of a foot pedal 20 which extends through an opening in the floor F. This pedal is provided with a lug 21 which is adapted to be received in a notch or recess 22 in the edge of the floor opening to hold said pedal in its depressed position. One end of a coil spring 23 is connected to the horizontal arm of the bell crank lever 18 and has its other end fixed to the vehicle floor. The depending arm of the lever 18 is provided with a plurality of openings 24 for the adjustable connection of the rods 17 thereto whereby the extent of movement of said rods upon the depression 30 of the foot pedal may be regulated.

In each of the lamp casings 5 inwardly of the doors 7 and 9, a sheet of glass or other transparent material 25 is arranged and suitably secured to the side walls of the lamp casing. It is usual to provide upon motor vehicles at the rear thereof and upon the left side, a red light, and the transparent plate 25 in the lamp case on the left side will therefore be colored green while the plate in the lamp case on the right will be colored red. The opposed faces of the doors 7 and 9 are painted or otherwise colored red.

In the operation of the invention as a day signal, the inner door 9 is connected at its free edge to the lamp casing 5 by means of the hook and eye 12 and 11. Thus when the operator depresses the pedal 20 with his foot, the rod 17 which is connected thereto is pulled forwardly and the cable or flexible connection 16 is unwound from the periphery of the wheel 15, thereby rotating the pintle rod 8 and swinging the outer door 7 to its open position. When this door has thus been opened, the red inner surface thereof and the red outer surface of the door 9 serve as a signal flag and indicate that the driver intends turning the machine to the left or right, as the case may be. The door 7 may be held open by simply forcing the upper end of the pedal 20 forwardly and engaging the lug 21 thereof in the notch 22 in the vehicle floor. When the pedal 20 is released, the spring 10 acts to 65 immediately return the door 7 to its closed

position and again wind the chain 16 upon the periphery of the wheel 15. In the use of the device as a night signal, the doors 7 and 9 are connected for unitary movement by engaging the hook 13 in the eye 11 so that when the pintle rod 8 is rotated in the manner above explained, both doors will be swung to their open positions so that the light of the lamp seen through the colored plates 25 will indicate to a person in the rear in which direction the driver intends to turn the vehicle. By providing the green colored plate 25 in the lamp case on the left, liability of confusion owing to the ordinary danger signal light carried by the vehicle at this point, is obviated.

From the foregoing, it is believed that the construction and manner of operation of my improved signaling device will be clearly understood. The box or casing 14 for the pulley 15 is supported upon an angular bracket plate 26 which is secured to the vehicle body and to the bottom of said box or casing. Either of the signaling devices may be quickly operated and is at all times under the control of the driver of the vehicle so that his intentions with regard to the direction of movement of the vehicle may be readily discerned by other motorists in the rear. The invention consists of comparatively few elements which are of simple form and provides an efficient and positively operating day or night signal of this character.

While I have shown and described the present preferred embodiment of the invention, it will be obvious that the same may be variously modified as required by the particular circumstances, without departing from the essential features or sacrificing any of the advantages thereof.

Having thus described the invention, what is claimed is:

1. In a signaling device of the character described, independently movable signal carrying elements, an additional stationary signaling element normally hidden from view by said movable signal elements, operating means for moving one of the signal carrying elements with respect to the other to display the signals carried by both of said elements, and means for connecting said elements for simultaneous movement upon the actuation of said operating means to expose the stationary signal to view.

2. In a signaling device of the character described a lamp case, a rotary pintle mounted upon said case, a door fixed to the pintle, a second door loosely mounted upon the pintle, means to connect said doors for unitary movement, and actuating means to rotate said pintle.

3. In a signaling device of the character described, a pair of hingedly mounted doors having a common pintle, one of said doors

being movable with respect to the other, said doors being provided upon their opposed faces with signaling means, a stationary signal normally hidden by one of the doors when in its closed position, operating means for rotating the pintle of said doors to move one of them to its open position to display the signaling means carried by said doors, and means for connecting said doors for movement as a unit to display the stationary signal.

4. In a signaling device of the character described, a lamp case; a rotary pintle mounted upon said case, a door fixed to said pintle, a second door loosely mounted upon the pintle, means to attach said latter door at its free edge to the lamp case or to the first named door for unitary movement therewith, the opposed faces of said doors being similarly colored, means connected to the first named door to normally hold the same in closed position, and manually operable means for rotating said pintle.

5. In a signaling device of the character

described, a lamp case, a rotary pintle 25 mounted upon said case, a door fixed to said pintle, a second door loosely mounted at one of its edges upon the pintle, means for attaching the latter door at its free edge to the lamp case or to said first named door, the 30 opposed faces of said doors being similarly colored, a colored transparent plate mounted in the lamp case, a peripherally grooved wheel fixed to one end of the pintle, a longitudinally movable rod, a flexible connection 35 between said rod and said wheel, a bell crank lever, said rod being adjustably connected to said lever, and a foot pedal connected to said lever to move said rod and rotate the pintle whereby one or both of the 40 lamp doors may be moved to their open position.

In testimony whereof I hereunto affix my signature in the presence of two witnesses.
